Patented Aug. 26, 1913.

UNITED STATES PATENT OFFICE

CORNELIUS F. COURSON, OF MEMPHIS, TENNESSEE.

LATCH DEVICE FOR WINDOWS, &c.

1,071,509.

Specification of Letters Patent. Patented Aug. 26, 1913.

Application filed March 25, 1913. Serial No. 756,715.

To all whom it may concern:

Be it known that I, CORNELIUS F. COURSON, of Memphis, in the county of Shelby and State of Tennessee, have invented certain new and useful Improvements in Latch Devices for Windows, &c.; and I do hereby declare the following to be a full, clear, and exact description of the invention, such as will enable others skilled in the art to which it appertains to make and use the same.

This invention relates to improvements in latch devices for windows, doors, screens, etc., the object of the invention being to so construct the latch devices that they may be used interchangeably for locking sashes together, for locking one or the other or both sashes to the window casing, or so that they may be employed to latch a door.

With this object in view, the invention consists in certain novel features of construction and combinations of parts as hereinafter set forth and pointed out in the claims.

In the accompanying drawings; Figure 1 is a view showing the application of my improvements to the meeting rails of window sashes; Fig. 2 is a view showing the application of the device for locking the bottom or the top sash or a screen to the sill or stile of a window casing. Fig. 3 is a view showing my improvements when used for latching a door, and Figs. 4, 5 and 6 are detail views of the latch devices.

1 represents a plate provided centrally with an enlargement 2 and having holes 3 near its ends for the accommodation of fastening devices. A latch button 4 is pivotally attached to the enlargement 2 of plate 1 and is provided with a thumb piece 5 for turning said latch button to cause it to engage or become disengaged from a keeper 6. The keeper 6 consists of a plate 7 having holes 8 for fastening devices, and an enlargement 9,—the base, top and one side of which are made with slots or recesses 10, 11, 12 respectively.

When my improvements are employed as means for locking two sashes together, the plate 1 carrying the latch button 4 will be

secured upon the meeting rail at the upper end of the lower sash and the keeper 6 will be secured to the lower meeting rail of the upper sash so the slot 12 in the side of the enlargement 9, as shown in Fig. 1.

To use my improvements to lock the upper or the lower sash of a screen frame to the stile or the sill of the window frame, the keeper 6 will be secured to the sash or screen frame near the upper or lower end thereof, and the plate 1 carrying the latch will be secured to the stile or sill in such position that the latch button can enter the slot 11 in the top or outer end of the enlargement of the keeper, as shown in Fig. 2.

When it is desired to employ the devices for locking a door, transom or similar hinged or swinging member, the plate 1 carrying the latch button will be secured to the door, and the keeper will be secured to the casing,—the enlargement 9 of the keeper being notched into the frame so as to dispose the base slot 10 in position to receive the latch button.

My improvements are simple in construction; are readily interchangeable for use in the various ways specified, and can be easily and quickly applied.

Having fully described my invention what I claim as new and desire to secure by Letters-Patent, is:—

1. The combination with a latch button, of a keeper having a plurality of engaging portions adapted for coöperation interchangeably with said latch button.

2. The combination with a latch button, of a keeper having a plurality of engaging portions for the button and adapted to be secured in place to permit any one of said engaging portions to receive the latch button.

3. The combination with a pivoted latch button, of a keeper having an enlargement provided with a plurality of slots open at different faces of the keeper, each slot adapted to receive said latch button according to the position in which the keeper may be secured with relation to the button.

4. The combination with a pivotal latch

button, of a keeper comprising a plate provided with an enlargement having slots in its base, side and outer end, each of said slots adapted to receive the button, according to the position in which said keeper may be secured with relation to the button.

In testimony whereof, I have signed this

specification in the presence of two subscribing witnesses.

CORNELIUS F. COURSON.

Witnesses:

J. E. BROCK,
B. H. GRIMME.
